(57) **CLAIM**

The ornamental design for a front fender of a motorcycle, as shown and described.

DESCRIPTION

FIG. 1 is a left side elevation view of a front fender of a motorcycle embodying our new design;

FIG. 2 is a right side elevation view thereof;

FIG. 3 is a bottom plan view thereof;

FIG. 4 is a top plan view thereof;

FIG. 5 is a rear elevation view thereof;

FIG. 6 is a front elevation view thereof;

FIG. 7 is a bottom and left side perspective view thereof;

FIG. 8 is a top and left side perspective view thereof; and,

FIG. 9 is a front and left side perspective view thereof.

The broken lines in the drawings illustrate portions of the front fender of motorcycle and boundaries thereof that form no part of the claimed design.

1 Claim, 7 Drawing Sheets
